UNITED STATES PATENT OFFICE.

JOHN C. MILLER, OF OAK PARK, AND LESLIE E. HOWARD, OF LA GRANGE, ILLINOIS, ASSIGNORS TO SIMONDS MANUFACTURING COMPANY, OF FITCHBURG, MASSACHUSETTS, A CORPORATION OF MASSACHUSETTS.

GRINDING-MACHINE.

No. 823,613.

Specification of Letters Patent.

Patented June 19, 1906.

Application filed December 27, 1904. Serial No. 238,400.

To all whom it may concern:

Be it known that we, JOHN C. MILLER, a resident of Oak Park, and LESLIE E. HOWARD, a resident of La Grange, county of Cook, and State of Illinois, citizens of the United States, have invented certain new and useful Improvements in Grinding-Machines, of which the following is a specification.

Our invention relates to grinding-machines of that general class employing a rotary ring grinding-wheel mounted on the lower end of a spindle and operating upon the article to be ground, which latter is given a reciprocating travel in contact with the grinding edge of the ring wheel.

The objections which have been encountered in this class of machines heretofore have been the inability of maintaining the surface of the work properly cooled to prevent withdrawing the temper, a stream of water when used being rapidly thrown off by centrifugal action, and thus rendered ineffective for its intended purpose. Dry grinding also produces an inferior finish and causes distortion through the effects of the heat generated on the article subjected to the machine. Furthermore, in machines of this class using an upright spindle heretofore, so far as we are aware, no provision has been made to counterbalance the gravity effect of the grinding-ring and its driving parts, with the result that where the grinding-ring has partial contact with the work, as where it passes off the ends of the latter, it produces irregularities in the ground surface.

Still another objection in prior machines relates to the amount of time and work involved in properly fitting and adjusting the work to the reciprocating bed preliminary to the grinding operation.

Our invention has for its primary object to eliminate the objections hereinabove specified, and this it accomplishes, in the first place, through the employment of means whereby the work and the grinding-surface of the machine are maintained constantly submerged in a cooling fluid; in the second place, through the provision of means whereby the gravity effect of the ring wheel and its operating parts is overbalanced and the ring wheel kept to its work through the pro-

vision of adjustable mechanism positively holding it there, and, in the third place, through the provision of magnetic means for holding the work in place, thereby dispensing with the necessity for any and all mechanical fastening devices.

Still other minor objects and advantages of the invention will appear later in connection with the following detailed description.

Our invention in its preferred mechanical embodiment is illustrated in the accompanying drawings, wherein—

Figure 1 is a side elevational view of the machine. Fig. 2 is a cross-sectional view on the line 2 2 of Fig. 1, certain of the parts appearing in front elevation. Fig. 3 is a longitudinal sectional view on the line 3 3 of Fig. 2. Fig. 4 is a detail plan view of an adjustable yoke in which is mounted the main carrying mechanism of the ring-wheel spindle. Fig. 5 is a detail perspective view of the belt-shifting mechanism, and Fig. 6 is a detail top plan view of a portion of the mechanism for effecting the angular adjustment of the ring wheel.

Referring to the drawings, 10 designates a stationary frame, and 11 the reciprocating bed-plate, corresponding to the form commonly used in the ordinary iron planer. The reciprocations of the latter over the former are effected from a main transverse driving-shaft 12 through a skew-rack 13 on the under side of the bed engaged by a skew-gear 14, mounted in the frame, the latter being driven from the driving-shaft 12 through the influence of suitable speed-reducing gears, which may comprise a pinion 15 on the driving-shaft meshing with the gear 16 of an intermediate shaft 17, this latter carrying a skew-pinion 18, engaging and driving the skew-gear 14. On either end of the driving-shaft 12 are fast and loose pulleys 19 and 20 and 19^a and 20^a, respectively, the former being operated from a suitable overhead source of power by a crossed belt 21, and the latter by an open belt 22. For reversing the movement of the reciprocating bed at the limits of its travel automatic means are employed to shift the belts 21 and 22 at such point. Such means may conveniently consist, as herein shown, of a belt-shifter bar 23, extending

across the machine-frame and carrying belt-engaging loops 24 and 25, said bar being actuated from the oscillations of a short shaft 26, mounted in the machine-frame, through the provision of an arm 27, formed to be alternately struck by tappets 28 and 29, depending from the side of the reciprocating bed, and connections from said shaft to the bar 23, which, as best shown in Fig. 5, may consist of an arm 30, a bell-crank 31, pivoted to the frame, and a link 32, connecting the free end of arm 30 with one arm of bell-crank 31, the other arm of the latter being connected directly to the belt-shifting bar 23. The connections of said bar to the belt are of course such that the movement of the bar carries the belt on one side from the fast to the loose pulley at the same time that it carries the belt on the opposite side from the loose to the fast pulley, and vice versa.

Mounted upon the reciprocating bed-plate 11, as by bolts 33, set into T-slots 34 in the bed-plate, (see Fig. 2,) is a water-tight box or tank 35, preferably of cast-iron and open at the top. In this box and secured to the bottom thereof, as by bolts 36, are one or more electromagnets, (a pair of such being herein shown.) These magnets each consist, preferably, of a cast-iron case 37, within which is a soft-iron core 38, surrounded by the windings 39 of the usual magnetic coil, around which windings is fitted in a water-tight manner a sheathing or covering of non-magnetic material, such as brass, (indicated at 40.) In the top member of the case above the magnetic coils is inserted a pair of magnetic insulating-strips 41, the purpose of which is to direct the magnetic lines of force around and over said strips through the material or work to be treated laid on top of said magnets, such work being herein indicated as a flat knife-blade 42. By this construction and arrangement it will be seen that the magnetic lines of force set up by passing an electric current through the coils of the magnets will necessarily be directed through the work 42 over the casing, which adheres rigidly to the upper face of the magnet while subjected to the grinding operation. In the preferred practice the magnet-containing case 37 is rendered substantially water-tight and is caused to direct the magnetic influence in the manner described by uniting the opposite halves of the case and the intermediate filling-strip lying between the non-magnetic division-strips 41 by means of non-magnetic bolts 43, drawing said parts tightly together. In order to drain off any possible leakage that may find its way within the case and for purposes of ventilation, the bottom plate of the case and its underlying supporting parts are provided with drain-ducts, (indicated by dotted lines at 44.)

Referring next to the ring wheel and the mechanism for supporting, driving, and ad-

justing the same, 45 designates each of a pair of side frame members or housings which rise from the stationary frame 10 on either side to a height considerably above the level of the reciprocating bed-plate. Secured to and between these housings and projecting forwardly over the bed-plate is a yoke 46, (shown in detail in Fig. 4,) said yoke having at its forward ends split journal-bearings 46^a for the trunnions 47^a of an upright yoke 47, 70 pivotally mounted therebetween. The yoke 47 is provided with upper and lower bearing members or casings 48 and 49, respectively, within which in suitable packing-sleeves and bushings is rotatably mounted a spindle 50, 80 carrying at its lower end the ring wheel or grinder 51, secured thereto, as herein shown, between fixed and removable washers 52 and 53, respectively, secured in place by a nut 54 on the lower end of the spindle. Secured to 85 the spindle 50 and fast by a key 55 is a pulley 56, adapted to be engaged by a suitable driving-belt to effect the rotation of the spindle and ring wheel at the desired speed. As hereinabove mentioned, a prominent feature 90 of our invention resides in the provision of means for normally overbalancing the ring wheel and its driving and adjusting parts, and, as herein shown, such means comprises a lever 57, fulcrumed at 58 on a stationary 95 bracket-arm 59, one end of said lever being forked and having pivotal connection with the upper end of the spindle through a trunnion-ring 60, mounted on the upper end of the spindle and secured in place by a nut 61, 100 rendered non-rotatable by a suitable key 62. The long arm of the lever 57 carries an adjustable weight 63. The upper and lower journal-bearings of the spindle are preferably constructed as follows:

Referring first to the upper bearing, (shown in sectional detail in Fig. 3,) 64 designates an inner sleeve of Babbitt or other soft metal forming a direct bearing member and confined endwise and circumferentially by a hard-metal sleeve 65, that is externally threaded and that engages an internally-threaded sleeve or bushing 66, of soft metal, that is in turn confined endwise and circumferentially by the outer casing 48 of the bearing. The hard-metal sleeve 65 is of reduced diameter at its lower end, where it surrounds the spindle, as shown at 65^a, and on such reduced portion is non-rotatably mounted, as by a feather 67, a worm-wheel 68, this latter being driven by a worm 69, journaled in a forwardly-projecting bracket 70 of the yoke and itself operated by a hand-wheel 71 on one end of the worm-shaft. The hand-wheel 71 might of course be substituted by an automatic feed, if desired.

72 designates a collar shrunk or otherwise fast on the spindle 50 between the upper end of the pulley 56 and the lower end of the reduced portion 65^a of sleeve 65. The collar 130

72 is normally held in contact with the lower end of sleeve 65 by the upward pull on the spindle created by the lever 57 and its over-balancing-weight 63. The lower bearing is generally similar to the upper bearing, comprising an inner bushing of Babbitt or other soft metal 73, confined circumferentially and endwise by a hard-metal sleeve 74, between which latter and the outer casing 49 is another soft-metal lining 75. The lower end of the sleeve 74 is slightly separated from the upper washer 52 of the ring wheel to permit of the vertical adjustment of the spindle through its bearings, such lower end of the sleeve preferably having an annular flange 74^a, that telescopes a short boss 52^a on the upper side of washer 52.

From the foregoing it will be seen that the tendency of the weight 63 through lever 57 upon the upper end of the spindle is to elevate the spindle and the ring wheel, which movement is resisted by the bearing of the collar 72 against the lower end of sleeve 65. By turning the hand-wheel 71 or its equivalent where an automatic adjustment is provided the threaded sleeve 65 is rotated in its threaded bearing in the stationary sleeve 66, whereby it rises or falls to a limited extent, according to the direction of adjustment. When adjusted upwardly, it permits a corresponding upward movement of the spindle and ring wheel, the collar 72 following such upward movement of the sleeve and limiting the extent of the vertical adjustment; but when operated in the opposite direction it effects a downward travel of the threaded sleeve, which, contacting the collar 72, fast on the spindle, forces the spindle and ring wheel downwardly against the elevating tendency of the weight 63. It will thus be seen that the gravity effect of the ring wheel and its driving parts upon the work is entirely eliminated and replaced by a direct pressure, the degree or extent of which is capable of exact adjustment by the mechanism last described. The ring wheel and its supporting and driving mechanism is capable of bodily vertical adjustment for adaptation to work of varying thicknesses, the means herein shown for such purposes comprising, essentially, a pair of vertical threaded rods 76, journaled at their upper ends in the upper ends of the housings 45 and engaging internally-threaded bearings in nuts 77, Fig. 4, secured to yoke 46, as by screw-bolts 78. The upper ends of rods 76 carry pinions 79, engaged by bevel-pinions 80 on a cross-shaft 81, suitably journaled across the tops of housings 45, said shaft carrying at one end an arm 82 and handle 83 or equivalent means for turning the same. By this mechanism the rotation of the shaft 81 through the threaded rods 76 bodily raises or lowers the spindle-carrying yoke 46, according to the direction of rotation.

It is sometimes desirable to set the ring-wheel at a slight angle normally to the work in order to effect a concave or hollow grind. A simple mechanism for effecting such an adjustment as herein shown comprises a bar 84, secured to one side of the vertical yoke 47 and at its other end carrying a block 85, provided with an elongated slot 86, this latter fitting over a threaded rod 87, mounted upon the rear portion of yoke 46, as best shown in the detail view in Fig. 6, the block 85 being secured at any desired adjustment on rod 87 by upper and lower clamping-nuts 88 and 89, respectively. In practice the angular adjustments of the spindle of the grinding-wheel are but slight, and these are easily and nicely effected by the mechanism last described.

In operation the top surface of the magnets having been thoroughly cleaned the knife-blade or other work 42 is laid thereon and secured thereto by magnetic attraction upon turning on an electric current through the coils of the magnets. The box or tank 35 is then filled with water or other cooling and lubricating fluid up to a height slightly above the upper surface of the work. The bed-plate and box are then set in motion by starting up the machine, the tappets 28 and 29 operating, through arm 27 and the belt-shifting mechanism, to effect the automatic reversal of movement of the bed-plate at its limit of travel in each direction. By means of the handle 83 the grinding-head is then lowered and roughly adjusted to the work, after which, by means of the hand-wheel 71, a nice adjustment of the grinding-head upon the work is effected, at which point the grinding edge of the ring wheel is slightly submerged beneath the upper surface of the water, as clearly indicated in Fig. 2, so that the grinding action takes place wholly beneath the level of the cooling or lubricating fluid. The normal tendency of the grinding-head being to rise, it follows that there is no uneven or unequal grinding produced when the grinding-head is partially removed from the work, as when passing off the ends of the latter. In case of hollow or concave grinding the arm 84 is adjusted on the threaded rod 87 to tilt the spindle of the grinding-head to such a degree as to effect the desired degree of concavity in the ground surface, the other adjustments of the spindle and head remaining as previously described. From the foregoing it will be seen that our invention effects the highly-important result of a submerged grinding wherein the cooling and lubricating fluid is necessarily in most intimate contact at all times with both the grinding and the ground surface, thus keeping down the heat produced by friction and preventing injury to the temper of the work and distortion of the latter through such heat, which feature we regard as a leading feature.

of the invention. The other benefits and advantages have already been fully mentioned and need not be here repeated.

It may be mentioned as an additional element of accuracy offered by the present machine that as a preliminary to the grinding operation the grinding-head may be lowered into contact with the upper surface or body of the magnets and run over the same to smooth and grind the latter to a true and perfect surface for the work subsequently laid thereon, and in view of the fact that a perfect replica of such surface is bound to be produced on the upper surface of the work it would follow that a true and uniform thickness is produced in the work by the grinding operation. It may also be mentioned that in grinding some knives one edge is ground thinner than the other. Such grinding may be effected by the machine herein described by sliding one of the bevel-pinions 80 out of engagement with its companion pinion 79, as indicated at the upper right-hand corner in Fig. 2, whereby the adjusting-rod 76 on but one side of the machine is operated. This results in tilting the grinding-head in a direction transverse to the work, thereby grinding off one edge of the latter more than the other.

We claim—

- 30 1. In a grinding-machine, the combination with a vertical spindle and a grinding-wheel mounted on the lower end thereof, of suitable bearings in which said spindle is journaled, means for driving said spindle, means for overbalancing the gravity effect of said grinding-wheel and its driving mechanism, and means for supporting the work against the grinding-face of said grinding-wheel, substantially as described.
- 40 2. In a grinding-machine, the combination with a vertical spindle and a grinding-wheel mounted on the lower end thereof, of suitable bearings in which said spindle is journaled with capacity for vertical adjustment, means for driving said spindle, means for vertically adjusting said spindle, means for overbalancing the gravity effect of said grinding-wheel and its driving and adjusting mechanism, and means for supporting the work against the grinding-face of said grinding-wheel, substantially as described.
- 50 3. In a grinding-machine, the combination with a vertical spindle and a grinding-wheel mounted on the lower end thereof, of suitable bearings in which said spindle is journaled with capacity for both vertical and angular adjustment, means for driving said spindle, means for vertically adjusting said spindle, other means for angularly adjusting said spindle, means for overbalancing the gravity effect of said grinding-wheel and its driving and adjusting mechanism, and means for supporting the work against the grinding-face of said grinding-wheel, substantially as de-
65 scribed.

4. In a grinding-machine, the combination with a grinding-tool and means for actuating the same, of a substantially water-tight work-supporting case, an electromagnet contained in the latter, means for directing the lines of magnetic force through said case and the work laid thereon so as to hold the latter to the former through magnetic attraction, and a tank containing said work-supporting case and adapted to be filled with water to a level above the surface of the work to be ground, substantially as described.

5. In a grinding-machine, the combination with a stationary frame, of a bed-plate reciprocable thereover, a tank carried by said bed-plate, a work-supporting device contained in said tank, a stationary housing rising above said tank, a horizontally-disposed yoke carried by said housing extending across said tank, a vertical spindle supported by said yoke, a grinding-wheel on the lower end of said spindle, means for driving said spindle, means for overbalancing the gravity effect of said grinding-wheel and its driving mechanism, and means for adjusting said grinding-wheel into operative contact with the work, substantially as described.

6. In a grinding-machine, the combination with a stationary frame, of a bed-plate reciprocable thereover, a tank carried by said bed-plate, a work-supporting device contained in said tank, a stationary housing rising above said tank, a horizontally-disposed yoke carried by said housing extending across said tank, a vertically-disposed yoke pivotally mounted in said horizontal yoke and containing bearings, a spindle mounted in said bearings, a grinding-wheel on the lower end of said spindle, means for driving said spindle, means for overbalancing the gravity effect of said grinding-wheel and its driving mechanism, and means for angularly adjusting said vertical yoke and said spindle mounted therein, whereby to effect concave or hollow grinding, substantially as described.

7. In a grinding-machine, the combination with a stationary frame, of a bed-plate reciprocable thereover, a tank carried by said bed-plate, a work-supporting device contained in said tank, a stationary housing rising above said tank, a vertically-adjustable horizontally-disposed yoke carried by said housing extending across said tank, an angularly-adjustable vertically-disposed yoke pivotally mounted in said horizontal yoke and containing bearings, a vertically-adjustable spindle mounted in said bearings, a grinding-wheel on the lower end of said spindle, means for driving said spindle, and means for overbalancing the gravity effect of said grinding-wheel and its driving mechanism, substantially as described.

8. In a grinding-machine, the combination with a grinding-tool and means for actuating the same, of a work-supporting case, an elec-
130

tromagnet contained in the latter, a water-tight sheathing or covering surrounding said electromagnet, means for directing the lines of magnetic force through said case and the work laid thereon so as to hold the latter to the frame through magnetic attraction, and a tank containing said work-supporting case and adapted to be filled with water to a level

above the surface of the work to be ground, substantially as described.
